UNITED STATES PATENT OFFICE.

PETER J. ROCK, OF SUPERIOR, WISCONSIN, ASSIGNOR OF ONE-THIRD TO
WILLIAM ROCK, OF SAME PLACE.

DESIGN FOR A BEATER OR STIRRER BLADE.

SPECIFICATION forming part of Design No. 30,015, dated January 17, 1899.

Application filed November 18, 1898. Serial No. 696,821. Term of patent 14 years.

To all whom it may concern:

Be it known that I, PETER J. ROCK, a citizen of the United States, residing at Superior, in the county of Douglas and State of Wisconsin, have invented and produced a new and original Design for a Beater or Stirrer Blade; and I do hereby declare the following to be a full, clear, and exact description of the same, reference being had to the accompanying drawing, forming a part thereof.

The accompanying drawing is a perspective view of a beater or stirrer blade embodying my design.

The leading feature of my design consists of a beater or stirrer blade comprising a shaft having a handle at its upper end and a rectangular plate at the lower end thereof, said plate being provided with openings.

A in the drawing represents a shaft which is bent at its upper end to form a crank *a*, 20 which latter is provided with a knob or handle *a'*. To the lower end of the shaft is secured a rectangular stirrer plate or blade *B*, which is formed with perforations *b*.

Having now described my invention, what 25 I claim as new, and desire to secure by Letters Patent, is—

The design for a beater or stirrer blade, substantially as herein shown and described.

In testimony whereof I hereunto affix my 30 signature in presence of two witnesses.

PETER J. ROCK.
